(57) **CLAIM**

The ornamental design for a display screen with a graphical user interface as shown and described.

DESCRIPTION

The patent or application file contains at least one drawing/photograph executed in color. Copies of this patent with color drawing(s)/photograph(s) will be provided by the Office upon request and payment of the necessary fee.

FIG. 1 is a front view of a first image in a sequence of a display screen with a graphical user interface showing our new design;

FIG. 2 is a second image thereof; and,
FIG. 3 is a third image thereof.

Portions of the graphical user interface are shown in broken lines, which form no portion of the claimed design.

The appearance of the transitional image sequentially transitions between the images shown in FIGS. 1-3. The process or period in which one image transitions to another image forms no part of the claimed design.

The outer perimeter broken line showing of a display screen forms no part of the claimed design. All other broken lines show portions of the graphical user interface that form no part of the claimed design.
